ACOUSTICAL TILE OR THE LIKE

Charles W. Allen, Jr., Chicago, Ill., assignor to United States Gypsum Company, Chicago, Ill., a corporation of Illinois

Filed Apr. 22, 1963, Ser. No. 74,539

Term of patent 14 years

(Cl. D18—2)

FIG. 1 is a top plan view of an acoustical tile or the like showing my design;

FIG. 2 is an edge view of said acoustical tile or the like; and

FIG. 3 is a partial sectional view taken along the line 3—3 of FIG. 1.

I claim:

The ornamental design for an acoustical tile or the like, substantially as shown.
